(57) **CLAIM**

The ornamental design for a display screen or portion thereof with graphical user interface, as shown and described.

DESCRIPTION

FIG. 1 is a front view of a display screen or portion thereof with graphical user interface showing my new design; and, FIG. 2 is an enlarged view taken from FIG. 1.

The dash-dot broken lines in the drawings illustrate the display screen or portion thereof and form no part of the claimed design. The dotted line rectangles in FIGS. 1 and 2 depict the boundary of the enlarged view and form no part of the claimed design. The dash-dash broken lines in the drawings illustrate portions of the graphical user interface that form no part of the claimed design.
